UNITED STATES PATENT OFFICE.

GEORGE M. DERRY, OF DANVERS, MASSACHUSETTS.

DOOR-OPERATING MECHANISM.

1,142,405.

Specification of Letters Patent.

Patented June 8, 1915.

Application filed August 25, 1913. Serial No. 786,573.

To all whom it may concern:

Be it known that I, GEORGE M. DERRY, a citizen of the United States, residing at Danvers, county of Essex, Commonwealth of Massachusetts, have invented certain new and useful Improvements in Door-Operating Mechanisms, of which the following is a specification.

This invention relates to door operating mechanisms and particularly to a mechanism for automatically operating the doors of an elevator shaft.

My present invention is especially designed for factory and mill use where low speed elevators are used and where both the side and trap doors of the elevator shaft are of the suspended type.

Considerable difficulty has been experienced in devising automatic door operating mechanism which would open and close both side and trap doors under the usual conditions and arrangements. It has been comparatively easy to open the top and bottom doors of the shaft by an operating mechanism on the elevator but when to this is added the difficulty of operating a door at an intermediate floor and furthermore that of not operating doors at certain floors the problem involved becomes difficult.

To the end therefore of providing a satisfactory and practical door operating mechanism of this nature I have devised my present invention. The principle involved in my invention is, briefly, that of operating the doors from the elevator through the medium of the door suspension means itself, thus materially reducing the number of operating parts necessary and lessening the cost of installation.

My present invention, therefore, broadly stated, resides in the combination of a door suspension means and an operating means on the elevator for taking up and releasing the suspension means.

The construction and principle of my invention will be more fully discussed in the specification which follows and as illustrative of the same I have shown in the annexed drawings an embodiment which has been found highly satisfactory in practice. It will be borne in mind, however, that owing to the limitations of space it has been necessary to exaggerate certain details in the drawings to adequately illustrate the construction involved.

Throughout specification and drawings

similar numerals of reference will denote corresponding parts and in these drawings: Figure 1 is a general view through an elevator shaft equipped in accordance with my invention, the doors of the landing at which the elevator is shown as stopped being open and all other doors at other landings being closed. Fig. 2 is a vertical central section through the shaft at that floor at which the elevator is represented as stopped and the doors opened in Fig. 1. Fig. 3 is a vertical section on the line 3—3 of Fig. 2 looking in the direction of the arrow. Figs. 4 and 5 are details of the side door operating parts. Fig. 6 is a detail of the trap door operating parts. Fig. 7 is a plan of the side door operating parts showing an adjusting feature whereby a door at a desired landing may be passed without operating, and Fig. 8 is a detail of one of the pinions for the trap door showing the arrangement for preventing rotation thereof at a certain point in the travel of the elevator.

I shall first describe the operating mechanism for the side doors of the elevator shaft.

Referring to Fig. 1, I have indicated at 1 a portion of an elevator shaft of the ordinary type having in one or both of its side walls door openings 2 at each landing 3 adapted to be covered and uncovered by gravity side doors 4 sliding in vertical tracks 5. Each door has fastened to its bottom by the bolt and slot connections 6, an offset vertically slideable bottom piece 7. This piece is an emergency device and comes into action when for any reason the free descent of the door would be obstructed as by a block lodging in the path of the door at a landing. Should this contingency arise the bottom piece 7 will strike the obstruction and through its sliding connections will rise up leaving the door suspending cables still under tension. The piece 7 does not slide in the door tracks 5 but tilts up from either end or the center according to where the obstruction strikes it. Each door is suspended near its upper edge by two sets of suspension cables 10 connected with a winding and releasing mechanism and actuated by an operating mechanism on the elevator. These devices will be described later, and inasmuch as both sets are identical a description of one set will suffice. Each cable 10 is connected near the center of the upper edge of the door to one end of a pair of oppositely disposed coil springs 11.

whose other ends are fastened to the door itself by a bracket 12. The purpose of these springs is to reduce the shock of the door descent. Each cable from its connection with the spring 11 passes through an eye 13 near the corner of the door up over two pulleys 14 mounted on a frame 9 secured to the shaft below each landing, thence partly across the elevator shaft to a third pulley 15 on said frame, and finally downwardly to a sheave or winding drum 16 mounted in a bracket 17 adjustable by two sets of slot and bolt connections 17' and 19' (see Fig. 7) on a wall bracket 19 in the elevator shaft. The adjustable connections 17' and 19' permit the bracket 17 to be moved back out of the way of the elevator when it is not desired to operate the door at a given landing. By having two sets of slot and bolt connections I am able to get a sliding adjustment of bracket 17, both toward and away from the wall and slightly across the same. This double adjustment also permits the pinion presently to be described to be positioned accurately with respect to the operating devices carried by the elevator and is particularly desirable where the parts have been inaccurately located in the assemblage. Set on the inner end of the same shaft that carries the sheave 16 is an operating pinion 21 the hub of which is slotted as indicated at 22 for a purpose which will presently appear. This pinion preferably has eight teeth which are of sufficient length and depth to provide adequate engaging surfaces for the operating mechanism on the elevator. This operating mechanism for the pinions consists of two vertically disposed spaced racks 23 and 23', numeral 23 indicating the upper and numeral 23' indicating the lower rack, fastened by brackets 24 and 24' to the suspension post 25 of the elevator 8 which carries the elevator shoes 26 which slide along the elevator guides 27 and the hoisting pulley 28 to which the hoisting cable 29 is connected. Each rack is formed as a straight standard, one half of which is plain and the other half provided with rack teeth. The arrangement is such that the rack teeth of one standard faces the plain part of the other standard leaving a space at the center where there are no teeth. The operating mechanism may therefore be called an oppositely disposed tandem rack. The upper rack 23 operates to raise the door as the elevator travels up the shaft. The lower rack 23' operates to lower the door as the elevator travels up the shaft. For the down trip these operations are reversed and the lower rack raises the door and the upper rack lowers it. The bracket 24 extends across the space at the center of the standards where there are no rack teeth and has slidably attached thereto by the screw and slot connections 31 a vertically

disposed dog 32 chamfered at each end and so positioned as to pass through the slot in the hub of the pinion 21 when the elevator brings that space of the rack bars where there are no teeth opposite said pinion. (See Fig. 4.) The dog therefore acts as a lock to hold the door open to its greatest extent at a landing. Referring to Fig. 5 the action of this dog will be more clear. In this figure the elevator is supposed to be descending. The last tooth of the lower rack 23' which operates first in the descent is shown as meshing with the pinion 21 and the lower chamfered end of the dog is disposed above the vertical axis thereof so as to readily engage and lie in the slot 22 of the hub of the pinion on the further movement of the elevator. The rack 23' is supposed to have descended to engage the pinion and rotate it and thus the winding drum 16 to wind up a door and at the point shown is just about to leave the pinion. The slot 22 in the hub of the pinion at this point lies diagonally with respect to the dog. As the elevator and therefore the rack and dog continue their descent, the rack will leave the pinion turning it enough, however, to bring the slot 22 into alignment with the chamfered end of the dog, whereupon the dog will enter said slot and lock the hub and thus the pinion against rotation at the point where there are no rack teeth. (See Fig. 4.) The pinion shaft being now locked and the sheave 16 being set on this shaft rotation of the sheave is therefore prevented and the door is locked in open raised position and can not descend to close while the car is at a standstill but must be released by starting the elevator either up or down to withdraw the dog from the slot. The dog being fixed to the elevator descends with it and soon leaves the slot, whereupon the upper rack 23 which is likewise descending, engages the pinion to rotate it and thus the winding sheave in reverse direction to lower the door. If the elevator instead of continuing down were returning up the shaft the action would be the same, the dog leaving the slot by reason of the upward movement of the elevator and the lower rack 23' which had just operated would return upwardly to again engage the pinion. The relation of rack and pinion teeth is therefore important to insure that the racks will release and take up the pinion at the proper moment to bring the slot into registration with the dog.

From the foregoing it will be seen that in the descent of the car, for example, the lower rack 23' first operates the pinion to raise a door at a landing, the dog then comes into action to lock the door against descent while the car is at a standstill and finally the upper rack 23 operates through the same pinion to lower the door as soon as the dog is withdrawn from slot 22 by starting the

car, or in the case of a return trip up, the lower rack 23' returns to engage the pinion and lower the door.

I shall now describe the mechanism for 5 operating the trap doors at each landing of the elevator shaft through the same racks on the elevator that operate the side doors.

Referring first to Fig. 1, I have indicated by the same numeral 33 two closed trap 10 door sections and at 33' an intermediate open trap door section. These door sections are hinged on pintles at opposite sides of the elevator shaft and swing from their centers up against the sides of the shaft.

15 Each door section is suspended by a suspension cable 35 which is fastened thereto at one end and passes up through a guide pulley 36 and over a sheave or winding drum 37 fastened to the wall of the shaft at a point 20 above the landing. Mounted on the shaft which carries this sheave is a pinion 38 of the same pitch as pinion 21 but having preferably only six teeth. A similar pinion 39 is mounted on a shaft journaled in bearings below the landing. The six-tooth pinion 38 although of the same pitch as the eight-tooth pinion is smaller in diameter 25 and will therefore not engage with the opposite rack of the set of tandem racks as will the eight-tooth pinion. It is therefore necessary to use the second pinion 39 set 30 so as to engage with the opposite rack and to couple these pinions by means of a suitable drive. A simple form of drive is 35 shown in Fig. 1 in which a pulley 40 is mounted on the shaft of the pinion 38 and a pulley 41 on the shaft of the pinion 39 and are connected together by a rope, belt or other connection 42. The upper pinion 38 40 of each couple has its hub flattened on one side as indicated at 42', Fig. 8, to travel along a projecting rib 34 on the standard of the rack 23'. This arrangement involves the same principle as does an intermittent gear riding into its period of rest, 45 the teeth on the six-tooth pinion being so positioned with respect to the teeth in the rack that the flattened part of the hub engages the rib of the rack just as the rack is 50 leaving.

The operation so far is substantially as follows: As the elevator ascends the upper rack bar 23 thereon will first engage and rotate the lower pinion 39 of one of the couples, which through its connection 40, 41 and 55 42 will rotate the winding drum 37 and through the suspension cable 35 will raise the trap door. Inasmuch as the trap doors fold up against the sides of the elevator 60 shaft it follows that they would interfere with the passage of the elevator shoes along the guide. To overcome this I have found it necessary to cut out a portion of the guide at each floor as indicated at 44 so that the 65 door will fit recess flush with the guide and

to fasten to the under faces of the doors a guide section 45 which when the door is folded up takes the place of the guide that has been cut out thus forming a practically continuous guide. The elevator shoe 70 engages this guide section 45 and holds it and thus the trap door up, in open position. As the rack 23 continues its upward movement it engages and rotates the pinion 21 which through the connections before described will raise the side door. At this point the upper pinion 38 of the couple has its flattened portion 42' bearing against the rib 34 of the standard of the lower rack 23'. The rack 23' will therefore slide along 75 the flattened hub of the pinion 38 without rotating this pinion. Both side and trap doors are now open. The side door will be held open as long as the car is at a standstill by the engagement of dog 32 and slot 80 22. The trap door will be held open as long as the car is at a standstill by the engagement of the elevator shoe with the guide sections thereof. As soon as the car has started up the shaft the lower rack bar 23' 85 will engage and rotate the pinion 21 to lower the side door and in its further movement will engage and rotate the upper pinion 38 at the moment it is clear of the upper rack 23 which pinion through the winding drum 90 95 and suspension cable will lower the trap door.

It is to be noted that in both types of my invention the doors are always under suspension and they are operated through the 100 medium of their suspension means. Considerable importance is attached to the fact that both the winding mechanism for the side door and the winding mechanism for the trap door are actuated by the tandem 105 racks on the elevator and do not require individual operating mechanisms.

Various modifications in the form and construction of my invention may obviously be resorted to within the limits of the appended claims.

What I therefore claim and desire to secure by Letters Patent is:

1. In combination an elevator shaft, suspended side and trap doors for said shaft, independent suspension means for said doors, a car in said shaft, a winding and unwinding mechanism for the suspension means of the side doors and an independent winding and unwinding mechanism for the suspension means of the trap doors, a single set of engaging elements carried by said car and disposed to successively and independently actuate the respective winding and unwinding mechanisms of the side and trap doors by imparting opposite rotative motion thereto, to successively open and close the doors in either direction of travel of the elevator.

2. In combination, an elevator shaft, an

elevator in said shaft, suspended side and trap doors, independent suspension means for said doors, a winding and unwinding mechanism for the suspension means of the side doors, an independent winding and unwinding mechanism for the suspension means of the trap doors, and a single operating mechanism for said sets of suspension means including oppositely disposed 5 engaging devices associated with the elevator and effective to successively and independently actuate the respective winding and unwinding mechanism of the side and trap doors by imparting opposite rotative 10 motion thereto to successively open and close the doors.

3. In combination, an elevator shaft, an elevator in said shaft, elevator doors of the suspended type, suspension means for said 20 doors, a winding mechanism for said suspension means including a slotted pinion, actuating elements associated with said elevator and effectively disposed to impart intermittent opposite rotation to said pinion 25 to open and close the doors, and a locking device associated with said actuating elements and having a locking engagement with the slot of said pinion when the elevator is at a stand still for locking the doors 30 in open position.

4. In combination, a moving body, a suspended closure, suspension means for said closure, an actuating mechanism associated with said moving body, a winding and unwinding mechanism for said closure including 35 a slotted pinion effectively disposed for actuation in either direction by the actuating mechanism and means coöperating with said slot in the pinion for locking said pinion against rotation when the moving body 40 is at a standstill.

5. In combination with suspension means for a door, an elevator movable past said door, a winding mechanism for the suspension means and effectively disposed in the path of said elevator, actuating means carried by said elevator for actuating said winding mechanism to open and close the door, and a slidable bottom section on said 45 door for insuring that the suspension means of said closure will always be under tension.

6. In an elevator shaft a door, an elevator, an operating mechanism for opening and closing said door including coupled 55 rotatable members one of which has a flattened engaging surface, and engaging elements carried by said elevator and disposed to rotatively engage said coupled members 60 successively in opposite directions, one of said elements having a sliding bearing on said flattened surface.

7. In an elevator shaft a door, an elevator, an operating mechanism for opening and closing said door including coupled 65

rotatable members one of which has a flattened engaging surface, and a pair of spaced oppositely effective engaging elements carried by said elevator and disposed to rotatively engage said coupled members 70 successively in opposite directions, one of said rotatable members and one of said engaging elements having a sliding engagement during a part of the travel of the elevator to prevent rotation of said member. 75

8. In an elevator shaft, a door, an elevator, an operating mechanism for opening and closing said door including a pair of coupled pinions one of which has its hub flattened, and engaging elements carried by 80 said elevator and disposed to rotatively engage said pinions successively in opposite directions, one of said engaging elements having a projecting flat bearing surface effective to slidably engage the flat part of 85 the pinion hub and prevent rotation of the pinion during a part of the travel of the elevator.

9. In combination, an elevator shaft, an elevator, suspended side and trap closures, 90 independent suspension means for said closures, a winding and unwinding mechanism for the suspension means of the side closures, an independent winding and unwinding mechanism for the suspension means of 95 the trap closures including coupled rotatable elements, and a single set of actuating elements associated with said elevator and disposed to successively and independently 100 actuate the respective winding and unwinding mechanisms of the side and trap closures.

10. In combination, an elevator shaft, an elevator, suspended side and trap closures, independent suspension means for said closures, a winding and unwinding mechanism for the suspension means of the side closures, an independent winding and unwinding mechanism for the suspension means of the trap closures including coupled rotatable 110 elements, and actuating elements associated with said elevator and disposed to successively and independently actuate the respective winding and unwinding mechanisms of the side and trap closures, one of said actuating elements having a sliding engagement with one of the coupled rotatable elements to prevent rotation of said element during a part of the travel of the elevator. 115

11. In combination, an elevator shaft, an elevator, suspended side and trap closures, independent suspension means for said closures, independent winding and unwinding mechanisms for the suspension means of both 125 sets of closures, an actuating mechanism associated with the elevator and disposed to successively and independently actuate the respective winding and unwinding mechanisms of both sets of closures, and a yielding 130

contact section at the lower edge of each side closure for insuring that the suspension means of said closures will be always under tension.

5 12. In combination, an elevator shaft, an elevator, suspended side and trap doors, independent suspension means for said doors, a pair of actuating elements on said elevator, a winding and unwinding mechanism for said suspension means of the side doors selectively movable into and out of the operative influence of the pair of actuating elements, and an independent winding and unwinding mechanism for the suspension means of the trap doors including coupled actuatable members disposed normally one within the operative influence of each actuating element.

10 13. In combination, an elevator shaft, an elevator, suspended side and trap doors, independent suspension means for said doors, a pair of actuating elements on said elevator, a winding and unwinding mechanism for said suspension means of the side doors selectively movable into and out of the operative influence of the pair of actuating elements, and an independent winding and unwinding mechanism for the suspension means of the trap doors including 25 coupled actuatable members disposed normally one within the operative influence of each actuating element, one of said actuating elements having a sliding engagement with one of said coupled actuatable elements to prevent actuation of that element during a part of the travel of the elevator.

15 14. In combination, a moving body, suspended side and trap closures, independent suspension means for said closures, independent winding and unwinding mechanisms for the suspension means of both sets of closures, and a single actuating mechanism associated with said moving body and effectively disposed to successively and in-

dependently actuate the respective winding 45 and unwinding mechanisms of both sets of closures.

15 15. In combination, an elevator, an actuating mechanism carried thereby, independently suspended side and trap doors, and independently acting opening and closing mechanisms operatively connected with the suspension means for said sets of doors actuated successively by said actuating mechanism on the elevator. 50

15 16. In combination, an elevator, a single actuating mechanism carried thereby, a suspended sliding side door, an independently suspended hinged trap door, and independently acting opening and closing mechanisms for both sets of doors actuated successively by the single actuating mechanism on the elevator. 60

15 17. In combination, an elevator, an actuating mechanism carried thereby, side and trap doors, independently acting opening and closing mechanisms for said doors, and a locking device adjustably mounted in said elevator and positioned for locking engagement with the opening and closing mechanism for said side doors and disposed out of the way of the opening and closing mechanism for the trap doors. 70

15 18. In combination, an elevator, an actuating mechanism carried thereby, a side door, an opening and closing mechanism for said door including a slotted engageable element in the path of said actuating mechanism and a double ended locking device for said engageable element having an entering 80 engagement in the slot of said element in either direction of travel of the elevator.

In testimony whereof I affix my signature in presence of two witnesses.

GEORGE M. DERRY.
